UNITED STATES PATENT OFFICE.

GEORGE A. NORCROSS, OF SAN ANTONIO, TEXAS, ASSIGNOR OF TWO-THIRDS
TO J. O. SULLIVAN AND G. R. SULLIVAN, OF SAME PLACE.

AUTOGRAPHIC REGISTER.

SPECIFICATION forming part of Letters Patent No. 568,454, dated September 29, 1896.

Application filed August 19, 1895. Serial No. 559,815. (No model.)

To all whom it may concern:

Be it known that I, GEORGE A. NORCROSS, a citizen of the United States, residing at San Antonio, in the county of Bexar and State of 5 Texas, have invented a new and useful Auto-graph-Register, of which the following is a specification.

My invention relates to autograph-registers; and the objects in view are to provide improved means for guiding, printing, cutting, and filing a record-bill and discharging original and duplicate bills; to provide improved means for operating the printing devices independently of the feeding mechanism, where- 10 by strips of any desired length to suit the length of the account or bill may be made; to provide means for dating checks and numbering them successively, the adjustment of the numbering device being automatic, and, 15 furthermore, to provide improved means for operating the filing mechanism.

Further objects and advantages of this invention will appear in the following description, and the novel features thereof will be 20 particularly pointed out in the appended claims.

In the drawings, Figure 1 is a perspective view of a register embodying my invention. Fig. 2 is a longitudinal section of the same. 25 Fig. 3 is a transverse vertical section on the line 3 3 of Fig. 2. Fig. 4 is a detail view, partly broken away, of the printing-roll. Fig. 5 is a transverse section of the writing-table on the line 5 5 of Fig. 2. Fig. 6 is a detail view, in longitudinal section, of the numbering devices. Fig. 7 is a detail view of one 30 of the numbering-disks. Fig. 8 is a transverse section through the dating device on the line 8 8 of Fig. 4. Fig. 9 is a side view, 35 partly broken away, of an autograph-register showing a slightly-modified form of filing device for the permanent or record bill. Fig. 40 10 is a detail view of a modified form of printing mechanism.

Similar numerals of reference indicate corresponding parts in all the figures of the drawings.

1 designates a casing or box provided at its upper side near one end with an inclined writing plate or table 2, over which pass paper strips from the supply-rolls 3, 4, and 5, said

strips extending through a feed-slot 6, near the lower edge of the writing-plate. The strips of the rolls 3 and 4 are reeled thereon in a common direction, and after passing through 55 the machine the checks from said rolls 3 and 4 form, respectively, the original and duplicate checks designed for the customer and the cashier, while the strip of the roll 5 is reeled in the opposite direction, and after passing over 60 the writing-plate and receiving the impression of the printing mechanism again returns to the interior of the casing and forms the record-checks. The object in reeling the strips upon the rolls 3 and 4 in one direction and 65 upon the roll 5 in the other direction is to cause the former, which produce the original and duplicate checks, to curl or bend upward at their front extremities, while the strip of the roll 5 curls downward at its extremity. 70 After passing over the writing-plate the strips extend over the printing-table 7 and between the feed-rolls 8 and 9, after which the upwardly-curved front edges of the original and duplicate strips pass above the plane of the 75 separator-lip 10, while the downwardly-curved extremity of the record-strip passes below the same and hence into the casing.

In order to cause a duplication of the record upon the duplicate and record strips as a bill 80 is made out upon the original strip, I employ duplicating or carbon paper 11, the desired number of sheets of which are reeled upon the spool 12 within the casing at one side of the printing-plate and adapted to be extended 85 transversely across said plate, respectively, between the main and duplicate and between the duplicate and record strips, as indicated in Fig. 5. The spool 12 may be spring-actuated to reel the duplicating-paper when released, such construction not being indicated in the drawings and being understood without further description. The free edges of the duplicating-strips are clamped to maintain said strips in their operative positions by 90 means of a clamp 13, having parallel side arms 14, connected at their front ends by a hinge-bar 15, mounted upon the writing-plate contiguous to the transverse feed-slot 6. After stretching the carbon-sheets transversely 100 over the writing-plate this clamping-frame is lowered to the position indicated in Figs. 1,

2, and 5 to secure the free edges thereof, after which the paper strips may be fed as desired and as heretofore described to form the checks.

5 Between vertical ears or extensions 16 of the side plates or walls of the casing is arranged the printing-roller 17, having terminal trunnions 18, which operate in horizontal guides or ways 19 in said ears or extensions 16, and said roller is advanced from one end of the guides or ways to the other by means of an operating-lever 20, connected to a rock-shaft 21, mounted transversely in the casing. The connections between this rock-shaft and the trunnions of the printing-roll consist of guide-pins 22, mounted in horizontal guideways 23 in the side walls of the casing and connected to the trunnions of the printing-roll by means of side bars 24, arms 25, fixed to the rock-shaft, and links 26, connecting the upper extremities of said arms with the guide-pins 22. Both the guide-pins and trunnions of the printing-roll are adapted to receive antifriction-rollers to operate in the guideways.

Connected to the trunnions of the printing-roll by means of links 27 are the inking and feeding rolls 28 and 29, the former being in contact with the surface of the printing-roll.

30 The printing-roll is preferably made hollow at one end for the reception of manually-operated dating-disks 30, and arranged contiguous to the other end of said roll are the numbering-disks 31, 32, and 33, arranged in parallel planes and mounted upon a common axis 34. These numbering-disks are provided with ratchet-teeth 35, and the disk 31, which is the units-disk, is actuated at each return or rearward movement of the printing-roll by 35 means of a pivotal pawl 36, arranged at a suitable point upon the contiguous ear 16 and adapted by reason of the beveled teeth to slip idly during the forward movement of the printing-roll. After the units-disk has 40 made a complete revolution motion is communicated to the tens-disk by a pin 37 on the units-disk engaging the ratchet of the tens-disk, said pin being brought into operative relation with the ratchet of the tens-disk by 45 means of a cam 38 on the units-disk engaging a projection 39 on the spindle 34 and moving said disk laterally against the tension of the spring 40, said spring 40 being designed to normally maintain the units-disk in its proper 50 position. In the same way motion is communicated from the tens to the hundreds disk at the end of each complete revolution of the tens-disk by means of a pin 41, which engages with the ratchet-teeth on the hundreds-disk, 55 and the tens-disk is moved to bring the pin 41 in engagement with the ratchet of the hundreds-disk by means corresponding with those above described for throwing the units-disk laterally to cause engagement of the pin 41 with the ratchet-teeth of the tens-disk.

In connection with the rock-shaft 21 I employ a return-spring 42, whereby when the

operating-lever 20 is released the printing-roll and connected parts are returned to the rear end of the printing-table and occupy the 70 positions indicated in Fig. 2, and in this position of the printing-roll it is out of contact with the printing-table by reason of a depression 43, formed in the latter at its rear end. When the handle is depressed to cause the 75 printing-roll to advance in the direction indicated by the latter in the guideway 19 in Fig. 2, the lowermost point of said roll is brought into contact with the printing-plate and rotary motion is imparted to the roll by 80 its frictional contact with the plate. During the return movement of the printing-roll the pawl 36 engages the ratchet-teeth of the units-disk and imparts a partial rotary movement to the latter sufficient to bring the next 85 numeral of said disk into the printing-plate or into such position as to come in contact with the printing-plate when the contiguous point of the printing-roll is in the printing position, and in the same way each return movement 90 of the printing-roll causes a forward movement of the numbering devices to secure the consecutive numbering of the checks.

Obviously, during the return movement of the printing-roll the rotation thereof causes 95 the printing-characters or type-faces to retrace or reimpress the printed surface.

In connection with the above-described mechanism for feeding and printing headings upon the checks, the feeding being accomplished by the rolls 8 and 9, of which one is provided with a crank 44, I employ filing mechanism including a filing-pin 45, having spring-coils 46, a filing-thread 47, extending through an eye 48 near the point of the filing-pin and extending from a supply-spool 49, and a filing-frame 50 for depressing the record checks or bills to impale them upon the filing-pin. The filing-frame is pivoted at 51 to the sides of the casing and extends beyond its pivotal point for connection by means of links 52 with the extremity of a rocking lever 53, said lever being fulcrumed at an intermediate point, as shown at 54, with its inwardly-extending arms 55 in the 105 path of projections or fingers 56 on the rock-shaft 21.

In order to sever the checks as they are formed, I employ a vertically-reciprocable knife 57, carried by vertical guide bars or arms 58, to the lower ends of which are connected the contiguous arms of bell-crank levers 59, and the other arms of said bell-crank levers are connected by means of links 60 with the arms 25, which communicate motion 110 to the printing mechanism.

Assuming that the heading of a check has been printed by the passage of the printing-roll over the printing-plate, the operation of the device is as follows: After the account of 115 sale or the desired list of articles has been written upon the original strip the crank 44 is turned to feed the strips forward until the lowermost line of writing on the original check

is beyond the plane of the knife 57, the front edge of the lower or record strip being passed within the casing below the plane of the filing-frame 50, and the original and duplicate strips 5 being passed out above the separating-lip 10. The operating-handle 20 is then grasped and depressed, thus simultaneously depressing the knife sufficiently to sever the checks from the strips and advancing the printing-roll 10 over the printing-table to print the heading of the succeeding check. After the rock-shaft 21 has been turned sufficiently to cause the severance of the checks from the strips the projections or fingers 56 come in contact with 15 the levers 53 and thus depress the front arm of the filing-frame 50, thereby forcing the record-check downward upon the filing-pin. When the operating-handle is released, the parts are returned to their normal positions 20 by means of the spring 42.

In Fig. 9 I have shown a slightly-modified arrangement of means for filing the record-checks, the same consisting in extending the lower or record strip 61 into the casing and 25 reeling it upon a roller or spool 62, which performs the additional function, in this case, of a feeding-roll and is provided with a handle 63. The strips are held in the proper positions in passing over the printing-plate 64 by 30 means of the pressure-roll 65, and in advance of this pressure-roll is arranged a fixed knife 66, by means of which the original and duplicate checks may be torn from the strips after they have been extended.

In Fig. 10 I have shown a slightly-modified arrangement of printing mechanism in which, instead of employing a roll, I use a flat plate or head 67, adapted, when not in use, to occupy a vertical position in contact with an 35 inking-pad 68, arranged contiguous to the plane of the knife 69. The rock-shaft 70, which is arranged in a position similar to that above described, is provided with arms 71, connected by links 72 and 73 with the printing 40 plate or head at different points. Concentric with these points of connection of the links 72 and 73 with the printing plate or head are guide-pins 74 and 75, adapted to operate in ways 76 and 77, whereby as the printing 45 plate or head is moved from the position shown in Fig. 10 it is turned through a quarter-circle and reaches the printing-plate 78 in a horizontal position.

Various changes in the form, proportion, 50 and the minor details of construction may be resorted to without departing from the spirit or sacrificing any of the advantages of this invention.

Having described my invention, what I 55 claim is—

1. In an autograph-register, the combination with a writing-plate, paper-supply rolls and feeding devices, of printing mechanism having a printing-roll adapted to traverse a 60 printing-table, the printing-table being depressed at one extremity of the path of the roll

to allow the roll to pass out of contact therewith, operating connections for the printing-roll, and inking devices, substantially as specified.

2. In an autograph-register, the combination with a writing-plate, paper-supply rolls and feeding devices, of a printing-roll adapted to traverse a printing-table and having its trunnions mounted in guideways parallel with 70 the plane of the printing-table, side bars mounted at their upper extremities upon the spindle of the printing-roll and provided at their lower ends with guide-pins operating in guideways parallel with the guideways for 75 the trunnions of the printing-roll, a rock-shaft, and connections between the rock-shaft and the lower extremities of said side bars, substantially as specified.

3. In an autograph-register, the combination with a writing-plate, paper-supply rolls and feeding devices, of a printing-roll adapted to traverse a printing-table and having its trunnions mounted in guideways parallel with 80 the plane of the table, inclined side bars depending from the trunnions of the roll and provided at their lower extremities with guide-pins operating in guideways parallel with the guideways for the trunnions of the printing-roll, a rock-shaft, and means for re- 85 turning the same to its initial position after 90 each advance movement, arms carried by the rock-shaft, and links connecting the extremities of said arms with the guide-pins of said side bars, substantially as specified.

4. In an autograph-register, the combination with a writing-plate, paper-supply rolls and feeding devices, of a printing-roll adapted to traverse a printing-table, consecutive-numbering devices carried by the printing-roll and adapted to be operated automatically during each movement of the roll, and operating connections for causing the roll to traverse the printing-table, substantially as 95 specified.

5. In an autograph-register, the combination with a writing-plate, paper-supply rolls and feeding devices, of a printing-roll adapted to traverse a printing-table, consecutive-numbering devices carried by the printing- 105 roll and including a numbering-disk, pawl-and-ratchet mechanism for imparting a step-by-step movement to said numbering-disk during each movement of the printing-roll, and means for imparting motion to the roll 110 to cause it to traverse the printing-table, substantially as specified.

6. In an autograph-register, the combination with a writing-plate, paper-supply rolls and feeding devices, of printing mechanism 120 including a printing-roll adapted to traverse a printing-table, a series of independently-movable numbering-disks carried by the printing-roll, means for imparting a step-by-step rotary movement to one of said disks at 125 each movement of the printing-roll, connections between the disks whereby motion is 130

transmitted from one to the other at intervals, and means for imparting motion to the printing-roll, substantially as specified.

7. In an autograph-register, the combination with a writing-plate, paper-supply rolls and feeding devices, of printing mechanism including a printing-roll adapted to traverse a printing-table, means for communicating motion to the printing-roll to cause it to traverse the table, and consecutive-numbering devices carried by the printing-roll and including a series of disks mounted for independent rotation upon a common spindle and for axial sliding movement toward each other, resilient devices for maintaining said disks in their normal relative positions, ratchets and pins arranged, respectively, upon the contiguous faces of the disks and adapted to be brought into engagement by the axial sliding movement thereof, a pawl adapted to engage the ratchet of one of the disks to impart a step-by-step rotary movement thereto at each movement of the printing-roll across the printing-table, and means for imparting axial sliding movement to the disks at intervals to bring said pins and ratchets into engagement and cause the transmission of rotary movement from one disk to the other, substantially as specified.
8. In an autograph-register, the combination with a writing-plate, paper-supply rolls and feeding devices, of printing mechanism including a printing-roll adapted to traverse a printing-table, means for operating the printing-roll, and consecutive-numbering devices carried by the printing-roll including independently-rotatable disks mounted upon a common spindle and adapted for axial slid-

ing movement thereon, resilient means for holding the disks in their normal positions, means for communicating motion from one disk to the next in series when sliding movement is imparted thereto against the tension of said resilient means, feeding devices for imparting a step-by-step rotary movement to one of the disks at each movement of the printing-roll across the printing-table, and coöperating cams and projections arranged, respectively, upon the disks and the spindle thereof to cause axial sliding movement of the disks and communicate movement from one disk to the other, substantially as specified.

9. In an autograph-register, the combination with a writing-plate, paper-supply rolls, feeding devices, printing and cutting mechanisms, and means for operating said printing and cutting mechanisms, the same including an operating-lever, of filing mechanism including a filing-pin, a pivotal filing-frame adapted to depress a check upon the filing-pin, a rocking lever, connections between the rocking lever and the filing-frame, and a finger carried by the operating-lever and adapted to engage and impart motion to the rocking lever at an intermediate point of its movement, whereby the printing and cutting mechanisms precede the filing mechanism in operation, substantially as specified.

In testimony that I claim the foregoing as my own I have hereto affixed my signature in the presence of two witnesses.

GEORGE A. NORCROSS.
